CLAIM

The ornamental design for a “portable cooking station
having grate and griddle,” as shown and described.

DESCRIPTION

FIG. 1 is a perspective view of a portable cooking station
having a grate and a griddle.

FIG. 2 is a front view of the portable cooking station of FIG.
1.

FIG. 3 is a rear view of the portable cooking station of FIG.
1.

FIG. 4 is a right side view of the portable cooking station of
FIG. 1.

FIG. 5 is a left side view of the portable cooking station of
FIG. 1.

FIG. 6 is a top view of the portable cooking station of FIG.
1; and,

FIG. 7 is a bottom view of the portable cooking station of
FIG. 1.

The features shown in broken lines form no part of the
claimed design.

The lighter solid lines denote surfaces and contours. Line
shading is not surface ornamentation.
